START-STOP REPEATER SYSTEM

Louis M. Potts, Evanston, Ill., assignor to Teletype Corporation, Chicago, Ill., a corporation of Delaware

Application November 30, 1934, Serial No. 755,253

8 Claims. (Cl. 178—71)

This invention pertains to telegraph systems and apparatus, and more particularly to telegraph repeating systems and apparatus.

In telegraph systems using comparatively long signal intervals, relay repeaters which renew the current value of each impulse but which may modify the length of the impulses slightly have been found satisfactory for some telegraphic purposes, but in systems where transmission is effected at high speeds, it becomes necessary to preserve the relative lengths of signal impulses as well as to renew the current strength thereof. Accordingly, regenerative repeaters have been designed for start-stop telegraph systems in which received signal impulses are reproduced and retransmitted in renewed strength and in faithful reproduction of their relative time values, thereby producing signal impulses and signal conditions equivalent to the originally transmitted signals. Transmission systems in which such repeating devices are connected usually effect transmission in both directions over a single line wire, and in such systems it is desirable that any repeating devices connected between two sections of a line repeat from either line section into the other in response to an initiation of transmission of signals in either line section.

An object of the present invention is to provide an impulse repeating device capable of operating at high speeds to transmit signals under the control of either line section into the other line section equivalent in strength and wave shape to the originally transmitted signals.

Another object of the invention is the provision of a mechanical repeater for start-stop telegraph systems to repeat each signal impulse from one line section to another, in which mechanical arrangements are provided for preventing reflection of impulses received from one line section for retransmission to an adjacent line section.

A still further object of the invention is the provision of a mechanical repeating device for start-stop telegraph systems wherein its driving motor is controlled automatically from either line section.

A specific object of the invention is the provision of a device capable of repeating impulses from one line section to another and recording characters indicative of the repeated impulses in different colors distinctive of the direction of transmission.

The above and other objects of the present invention are attained by the provision of motor driven mechanically operated but signal controlled repeating device for repeating all signals

including start and stop signals and character signals from one line section to another, with elements either electrically or mechanically controlled for establishing reflection estoppel conditions at the beginning of the transmission of code combinations of impulses which continue until the end of such code combination of signal impulses.

Specifically, the apparatus of the invention 10 comprises electrical relays and circuits controlled by electrical switches which are controlled by start-stop cams provided upon the start-stop mechanism of the regenerative repeating devices, also motor-control devices operable by either of 15 two regenerative repeating devices to control a motor which supplies mechanical power for both of the regenerative repeaters, and also ribbon shifting or record modifying means controlled by start-stop cams and by circuits of the regenerative repeaters to indicate the direction of transmission of the intelligence impulses.

The circuits of the present invention in which 20 directional control is exercised comprise two regenerative repeater mechanisms so associated 25 with retransmitting contacts that the initial operation of either device sets up an estoppel condition which prevents reflection signals. The circuits of the present invention in which a single 30 regenerative repeater mechanism is used comprise a signal-receiving line relay for each line section and a repeating-mechanism-seizing relay for each line section, the line relay which initiates transmission operating to energize first 35 the seizing relay which then operates to seize the repeating mechanism in an alternative manner which determines its direction of repeating with reference to the two line sections. A locking circuit thereafter maintains this condition during the 40 then ensuing code cycle. In a modification wherein mechanical control is exercised, a mechanical locking member performs the function of the electrical locking circuit just described.

A better understanding of the invention may 45 be had from the following description, taken in connection with the accompanying drawings, wherein:

Fig. 1 shows a circuit system comprising two 50 line sections connected together through two regenerative repeating devices having polarized line magnets, the system operating upon two-current principles using polar signal impulses, transmission from a first terminal station to a second being recorded upon one printer and transmission in reverse direction from the second termi-

nal station to the first being recorded upon another printer;

Fig. 2 shows a circuit system comprising two line sections connected together through two regenerative repeating devices having neutral line magnets, the system operating upon single-current principles in which signal impulses comprising time periods of current are separated by signals comprising time periods without current;

Fig. 3 shows a circuit system comprising two line sections connected together through one regenerative repeating device which operates alternatively to repeat signals from one line section and into the other, the system operating upon single-current principles, and also having cam controlled locking relays whereby interruption of transmission at a mean signal impulse of a code combination of signal impulses is prevented;

Fig. 4 shows a circuit system similar to that shown in Fig. 3 but adapted to interconnect a line section having two-current working with a line section having single-current working;

Fig. 5 shows an alternative form of circuit system comprising two line sections connected through one regenerative repeating device arranged with means operable in response to each transmitted character for shifting a two-color ribbon in the receiving printer, the ribbon mechanism being shiftable in one direction to indicate one color to indicate transmission in one direction and the other color indicating transmission in the opposite direction;

Fig. 6 shows a circuit system of two line sections and a mechanical system of interlocking members connecting two regenerative repeater mechanisms which connect the line sections together in a single telegraph transmission line, any reflection signals being mechanically prevented, and

Fig. 7 shows a motor control system wherein either of two connected regenerative repeaters may control one motor which drives the two regenerative repeaters.

As disclosed in Fig. 1, a system according to this invention embodies two terminal stations A and B having their individual lines 2 and 3 respectively, terminated at a repeating station C. Each of the terminal stations is provided with a receiving printer 4 of polar-control construction and a transmitter 5, both receiving printer 4 and transmitter 5 being suitable for transmission under two-current principles, the receiving printer having a two-position armature 6 which takes one or the other of its two positions according to the polarity of the instant controlling current, and the transmitter 5 is provided with a battery of positive or marking polarity connected through resistor 7 to a contact in transmitter 5 and with a battery of negative or spacing polarity connected through resistor 8 to a contact in transmitter 5. The details described are shown diagrammatically at terminal station A, while terminal station B is similarly equipped. There is also arranged at each of the terminal stations an interrupter key 9 connected in the circuits of the terminal station in such manner that when in its operated position it will disconnect the receiver printer 4 and the transmitter 5 from the line 2 and will connect the line 2 to negative or spacing battery through resistor 8; also a motor 11 supplied with electrical energy over a circuit (not shown) serving to supply motive power to the receiving printer 4 and transmitter 5 as is well known. The circuit of the driving motor

11 may be controlled automatically by telegraphic signals in the line 2 as is well known.

As previously indicated, each of the lines 2 and 3 extends from the respective terminal stations to the repeating station C, and included in each of the lines is a line magnet 12 and 13 respectively. These line magnets are normally energized from batteries at the terminal stations A and B under control of contacts in transmitter 5 at each of the terminal stations. The circuit for effecting the energization of line magnets 12 and 13 extends in the case of terminal station A from ground at repeating station C through resistor 14, winding of magnet 12, contacts 15, line 16, spring and lower contact of interrupting key 9, winding of receiving printer magnet 4, transmitter 5, and resistor 7 to positive or marking battery. A circuit for line magnet 13 may be traced similarly through resistor 16, contact 17, and line 3 to terminal station B and to positive or marking battery.

Polar magnet 12 and its armature 21 comprises a selector magnet of a start-stop regenerative repeater 20 of the form and construction shown in copending application Serial No. 711,479, filed February 16, 1934.

According to the disclosure of the aforementioned copending application, the regenerative repeater is similar in construction to the printing telegraph device described in Patent No. 1,821,110 issued to S. Morton et al. September 1, 1931 and embodying a cam drum 22 arranged with the stop arm 23 normally in engagement with a fixed stop 24. The cam drum 22 has six

35 pairs of cams 25 which control six selecting levers 26 in accordance with six received intelligence impulses to operate the selector levers in sequence to register each intelligence signal impulse of a code as the impulses are received, 40 after which a transfer action occurs to transfer the six registrations simultaneously to the selector mechanism and to the printing mechanism of the receiving printer. Also carried by drum 22 are two multiple cam rings 30 and 31, which

45 are shaped to represent all of the cams 25, and in longitudinal alignment therewith and two additional cams representing start and stop signals of a start-stop code. Arranged in coaxial alignment with the six selector levers 26 is a repeater selector lever 32 moved into marking and spacing positions in a manner similar to the operation of selector levers 26 but operating for every impulse of the entire signal including the start and stop impulses. With every movement of lever 32, a striker 33 is operated to change the

50 contactive relation of contact members 34, 35, and 36 for the purpose of transmitting impulses in a controlled line section corresponding in strength and wave shape to the impulses received for controlling the operation of cam drum 22. Normally cam drum 22 is in its marking position with selector magnet 12 energized, in which case the stop arm 23 is in engagement with the fixed stop 24. Upon receipt of a spacing

55 signal indicative of a start condition generated by transmitter 5 at terminal station A, selector magnet 12 will be energized to move its armature 21, which will permit cam drum 22 to free stop arm 23 from fixed stop 24, and since driving motor 37 is now supplying power to the regenerative repeater, having been started automatically in any well-known manner in response to the change of signal in magnet 12, cam drum 22 is likewise rotated. Selecting magnet 12 and its

60 armature 21 will respond to the operation of

transmitter 5 at terminal station A and cause the cam drum 22 to be moved correspondingly and thus bring the cam rings 30 and 31 into operative relation with the selector lever 32 for causing the corresponding operation of contact members 34, 35, and 36. Simultaneously with the operation of selector lever 32, the selecting levers 26 will be operated through cams 25 for setting the selector mechanism of the printer to record the corresponding characters. The operation of contact members 34, 35, and 36 will generate in the line conductor 3 connected thereto impulses corresponding to the impulses which effected the energization of selecting magnet 12.

Assume that terminal station A desires to transmit a message to terminal station B, interrupter key 9 will be momentarily operated into its reverse position, resulting in the reversal of polarity of the current in line 2 and in the reversal of polarity of the energized polar selector magnet 12 at the repeating station C. Motors 11 and 37 are started automatically by means not shown, and motive power thus is applied to transmitter 5 and receiving printer 20. Also as a result of the momentary operation of interrupter key 9, line magnet 12 reverses the position of its armature 21, thus releasing cam drum 22 which by a slight axial movement frees stop arm 23 from its fixed stop 24. Immediately thereafter a cam of multiple cam ring 31 engages repeater selector lever 32, which responds and moves striker 33, thus changing the contactive relations of the contact members 34, 35, and 36, opening repeating contacts 17 and closing repeating contacts 38 and thereby changing the signal current in line 3. The circuit for current in line 3 now extends from positive battery 39 of double potential value through resistor 41, closed contacts 38, line 3, interrupter key, receiving printer magnet, and resistor of terminal station B and through positive battery of single potential value to ground. Normally line 3 carries a current in marking direction which causes the printer magnet to hold its armature in non-operating position, but in the circuit just traced, the double potential of marking battery 39 at the repeating station C overpowers the single potential of marking battery at terminal station B, thus reversing the direction of polarity of current in line 3 and through the printer magnet of station B. The printer magnet of terminal station B reverses its armature and starts its motor. Upon restoration of interrupting key 9 at terminal station A, the normal marking current is restored to the line 2, the magnet 12 reverses its polarity and restores its armature at the repeating station C, which causes selector lever 32 to return to its normal position, restoring the repeating contact members 34, 35, and 36 to their normal positions, closing repeating contacts 17, and opening repeater contacts 38; thus restoring the normal condition of circuit and current to line 3, restoring the marking polarity to the receiving printer magnet at the terminal station B, which returns its armature to its normal position. All motors having been started by this operation of the interrupting key 9 at terminal station A, the operator at station A may send a message.

Movement of transmitter 5 connects its tongue to spacing contact and connects negative battery through resistor 8 and transmitter 5, receiver magnet 4, key 9, line 2, contacts 15, magnet 12 of repeater 20 and resistor 14 to ground, thus reversing to spacing position the armatures 6

and 21 of magnet 4 and of repeater magnet 12 respectively. The reversal of armature 21 reverses the contactive relation of contact members 34, 35, and 36, thereby connecting positive battery 39 through repeater contacts 38 to line 3, through printer magnet and transmitter to positive battery and ground whereby the double potential of battery 39 overcomes the potential of the terminal station battery and reverses the position of the armature of printer at station B into spacing position, thereby repeating at terminal station B the signal originated in terminal station A. Meanwhile, movement of contact 35 away from contact 34 has opened the circuit of the magnet 13 of the repeater of line 3 which, having a polarized armature with a permanent field, is held by its permanent field in its marking condition and which, therefore, does not repeat the spacing condition into the line section 2. 15 When transmitter 5 restores its tongue to its marking contact at the termination of the spacing signal, positive battery at terminal station A restores the direction of current in line section 2, restores armature 21 to its marking condition, and restores repeater 20 to its marking condition, 20 which restores contact members 34, 35, and 36 to the contactive relation illustrated, thus removing line wire 3 from source 39 and restoring it to ground connection through the magnet 13, 25 thereby supplying marking current again to the magnet 13 without operating its armature since it has remained in marking position, and also restoring current from positive battery at terminal station B to central office ground through the magnet of the printer at terminal station B, 30 thereby restoring the armature of that printer to marking condition, thus repeating in the printer at terminal station B the restored marking signal originated in transmitter 5 at terminal station A. Interruption of transmission may be effected by shifting the tongue of the interrupting key at terminal station B to its spacing contact for a short period of time, thus connecting negative battery to line 3 whereupon 35 either forthwith or at the end of the instant signal if spacing, the negative battery at terminal station B will become effective and will reverse the signalling condition of the repeater magnet 13 and of its repeating contact members, and thus 40 will connect double marking potential 39 through line 2 to terminal station A, after which the printer 4 at substation A will be unresponsive to the transmitter 5 since current from battery 39 will flow in spacing direction through the magnet of printer 4 in either position of the tongue of transmitter 5 and to either of the terminal station batteries, by which non-response of printer 4, the operator at terminal station A will note that terminal station B is interrupting and desires to transmit.

60 During all interchange of transmission between the two terminal stations A and B, all transmission originated at station A will operate magnet 12 of printer 20 and will be recorded upon printer 20, while all transmission originated at station B will operate magnet 13 and will be recorded upon the printer of magnet 13. Thus at the repeating station C the direction of transmission whether from terminal station A or from terminal station B will be indicated and identified by the identity of the printer at station C upon which the transmission will have been recorded.

65 In Fig. 2 is disclosed a system according to this invention embodying two terminal stations D and E having their individual lines 42 and 43

respectively terminated at a repeating station F. Each of the terminal stations is provided with a receiving printer 44 of neutral-control construction and a transmitter 45, both receiving printer 44 and transmitter 45 being suitable for transmission under single-current principles. Terminal station E is similarly equipped. There is also arranged at each of the terminal stations D and E an interrupter key 46 connected in series with the line circuit, to open the line circuit, also a motor 47 which may be controlled automatically by line signals through means not shown. As in the case of the system of Fig. 1, each of the lines 42 and 43 extends from the respective terminal stations to the repeating station F and included in each of the lines is a line magnet 48 and 49 respectively, which are normally energized from batteries adjacent thereto. The circuit for effecting the energization of the line magnet 48 extends from battery through magnet 48, contacts 51 and line 42, interrupting key 46, printer magnet 44, and closed contacts of transmitter 45 to ground at terminal station D. A similar circuit may be traced through line magnet 49, contacts 52, and line 43 to ground at terminal station E.

Similarly to the printer 20 in Fig. 1, line magnet 48 and its armature 53 comprise a selector magnet of a start-stop regenerative repeater 54 which operates as a printer and also operates its repeating contact members 55 and its repeating contacts 52 and 56 in the manner which has been described above in connection with the description of Fig. 1.

Assume that terminal station D desires to transmit a message to terminal station E, interrupter key 46 will be momentarily operated, which opens its contacts thus opening the circuit of line 42, resulting in the deenergization of magnet 48 and the release of its armature 53 at the repeating station F. Motors 47 and 57 are started automatically by means not shown and motive power thus is applied to transmitter 45 and receiving printer 44. Also release of armature 53 has released the cam drum of printer 54, which shifts axially and starts into rotation. Immediately thereafter its repeater selector lever changes the contactive relations of its contact members 55, opening repeating contacts 52 and closing repeating contacts 56. Normally line 43 carries current as a marking signal which causes the printer at terminal station E to hold its armature in non-operating position, but since the circuit of line 43 has been opened at contact 52, the line current ceases, thus releasing the armature of the printer and starting the motor at terminal station E. Upon restoration of interrupting key 46, the normal marking current is restored to line 42, magnet 48 becomes energized and attracts its armature at the repeating station F, which causes the selector lever to return to its normal position, restoring the repeating contact members 55 to their normal positions as shown, thus restoring the normal condition of current in line 43, which returns terminal station E to its normal condition. All motors having been started by this operation of interrupting key 46, the operator at terminal station D may send a message. Every movement of transmitter 45 controls magnet 48 to repeat the movement, and magnet 48 in turn controls its cam drum and repeater selector lever to operate the repeating contact members 55 which, when thus controlled, repeat into line 43 every signal generated in line 42 by transmitter 45, thereby repeating at

terminal station E all signals originated at terminal station D. Meanwhile, opening of repeating contact 52 has opened the circuit of magnet 49 which had extended from battery through magnet 49 and contact 52 to line 43 and to ground at terminal station E. In the operation of contact members 55, contact 56 is closed before contact 52 is opened, thus providing in advance a substitute circuit for magnet 49, extending from battery through magnet 49 and contact 56 to ground 50. This substitute circuit constitutes a reflection estoppel circuit and magnet 49 therefore does not repeat any transmission signals into the line 42. Interruption of transmission may be effected by opening the interrupting key at terminal station E for a short period of time, thus opening the line 43 whereupon either forthwith or at the end of the instant signal, if spacing, the open line 43 will deenergize the line magnet 49, which will operate its associated repeater to open the line 42, after which the printer 44 at terminal station D will be unresponsive to the transmitter 45 since no current can flow in line 42, by which non-response of the printer 44, the operator at terminal station D will note that terminal station E is interrupting and desires to transmit.

According to the foregoing description of the apparatus embodied in Fig. 2, reflection estoppel is achieved from either line 42 or 43 by energizing, under local control, the electromagnet of the companion repeating mechanism and thus preventing its operation and the transmission of signal impulses to the line conductor under its control. Specifically, let it be assumed that transmission is from line 42 to line 43. Electromagnet 48 of repeater 54 is included in such circuit and responds to the impulses impressed on line 42 due to the operation of the transmitter 45 and effects the corresponding control of cam drum 54A, and the operation of selector lever 54B which closes contacts 56 and opens contacts 52. However, contacts 56 close before contacts 52 open resulting in continuing the circuit for electromagnet 49 which now extends from grounded battery, winding of electromagnet 49, contact spring 55, contacts 56, and resistance 58 to ground 50. Under such conditions, electromagnet 49 is maintained energized, the cam drum controlled thereby remains stopped, and contacts 51 are not opened so that printer 44 will not respond to the operation of contacts 52, and reflection of signal impulses on line 42 is thus prevented.

During all interchange of transmission between the two terminal stations D and E, all transmission originated at station D will operate magnet 48 of printer 54 and will be recorded upon printer 54, while all transmission originated at terminal station E will operate magnet 49 and will be recorded upon the printer of magnet 49. Thus at the repeating station F the direction of transmission, whether from terminal station D or terminal station E, will be indicated and identified by the identity of the printer at station F upon which the transmission will have been recorded.

Referring now to Fig. 3, there is disclosed an embodiment of the invention similar in some respects to the system disclosed in Fig. 2, except that there is but one regenerative repeater mechanism at the repeating station which serves both sections of a single line repeater system. Each of the terminal stations G and H has an individual line 61 and 62 respectively, also at each of the

terminal stations there is a transmitter 63, a receiving printer 64, an interrupting key 65, and a motor 66 with signal-control means, not shown, which may be of any desired type. Each of the lines 61 and 62 to their respective terminal stations includes at the repeating station K a line relay 67 and 68 respectively. Line relay 67 is normally energized by a circuit extending from grounded battery 58, resistor 69, contact 70 of de-energized relay 71, winding of line relay 67, line 61, interrupting key 65, magnet of receiving printer 64, and closed contacts of transmitter 63 to ground. A similar circuit may be traced through battery 58', resistor 69', contact 72 of deenergized relay 73 over line 62 to ground at terminal station H. At the repeating station K there is provided a single regenerative repeater mechanism 75 identical with the mechanism 54, Fig. 2, comprising printing and repeating mechanisms and comprising also an additional element, a cam 76 fixed to the cam drum 22, Fig. 1, which controls a contactive arrangement of three contact members to open one and close the other of two local switching contacts 77 and 78. These contacts control the application of battery to and removal of battery from certain switching and controlling circuits to be described within the repeating station. While cam 76 is in normal position, as shown in the drawings, the contact 77 is closed and the contact 78 is opened, but at all times when cam 76 is out of its normal position, the reverse is true and contact 78 is closed while contact 77 is opened. Each line 61 and 62 has also a local relay or seizing relay 73 and 71 respectively, each of which is operated in a manner to be described for the purpose of seizing the regenerative repeater mechanism 75 for the exclusive use of its associated line 61 or 62. The energizing circuit for relay 73, formed by relay 67 in response to a signal of open circuit nature originated at break key 65, may be traced from grounded battery 59 through contact 71, lower winding of relay 73, back contact and armature of deenergized line relay 67, and front contact and armature of energized line relay 68 to ground, the relay 73 being provided also with a locking winding whose circuit may be traced from grounded battery 59 through contact 78, upper winding of relay 73, and through contact and upper armature of relay 73 when energized, to ground. Similar circuits may be traced for energizing and locking windings of seizing relay 71. The operating magnet 79 in regenerative repeating mechanism 75 is included in a local repeating circuit extending from grounded battery 59' through the winding of magnet 79, wire 80, front contact and armature of line relay 67, and front contact and armature of line relay 68 to ground. The operating magnet 79, therefore, may be controlled by the front contact of either of the two line relays 67 and 68, while the back contacts of the two line relays control the energizing windings of their local seizing relays 73 and 71 respectively. Each seizing relay also shunts the front contacts of its opposing line relay and connects its opposing line section to the repeating contacts 81 of the regenerative repeater mechanism, as will appear in the description of operation now to be given.

Assume that terminal station G desires to transmit a message to terminal station H, interrupting key 65 will be momentarily opened resulting in the deenergization of relay 67 which deenergizes repeater operating magnet 79 which results in starting rotation of cam 76. Relay 67

also by its back contacts establishes the described energizing circuit for seizing relay 73, which will energize and operate its contacts, interrupting the normal circuit of the opposing line 62 and providing a new circuit for that line, which may be traced from ground at terminal station H over line 62, winding of line relay 68, contacts 72 of seizing relay 73 now energized, repeating contact 81, resistor 60' and battery 60 to ground. The regenerative repeater mechanism now continues in rotation and operates its cam contacts 77 and 78, immediately thereafter opening its repeating contacts 81, thus opening the circuit traced just above for line 62 and thus repeating into line 62, and to terminal station H the starting signal generated in line 61 by break key 65 at terminal station G. Opening the cam contact 77 has opened the energizing circuit of seizing relay 73, but before opening the energizing circuit, a holding circuit was closed through contact 78 and closed upper contacts of relay 73. A subsequent marking signal is generated by closing interrupting key 65 which reenergizes line relay 67 which in turn reenergizes operating magnet 79 of regenerative repeater mechanism 75, resulting in closing the repeating contact 81, thus repeating into line 62 and to terminal station H the marking signal generated by closing the interrupting key 65. A starting impulse of spacing nature in a start-stop code of signals will operate as does the opening of the interrupting key described above, after which, throughout the separate and several signals of the ensuing code combination of signals generated by transmitter 63, line relay 67 will repeat the separate signals to magnet 79 of regenerative repeater mechanism 75, which then will repeat the separate signals by action of repeating contacts 81 into the line 62 and to the terminal station H. At the end of a start-stop code group of signals, transmitter 63 will close its contact to generate the stop signal of the code group, cam 76 will complete its cycle of revolution, and the entire system will be restored to its condition of rest. Transmitter 63 immediately may seize the system for transmission of another code combination of signals, or at this time terminal station H may interrupt the transmission.

Interruption of transmission may be effected by opening the interrupting key at terminal station H for a short period of time, thus opening the line 62, whereupon, but not until the end of the instant code combination of signals, or not until the cam 76 has restored its contacts 77 and 78 to normal, the open line 62 will deenergize the line magnet 68 which will operate its associated seizing relay 71 and will seize the regenerative repeater mechanism 75 to open the line 61, after which the printer 64 at terminal station G will be unresponsive to its transmitter 63 since no current can flow in line 61, by which non-response of the receiving printer 64, the operator at terminal station G may be advised that the terminal station H is interrupting and desires to transmit.

Reflection estoppel, in the case of the structure of Fig. 3, is achieved by arranging control relays under the control of contacts operated by a cam of the repeater unit. Such control is effected by contacts 77 and 78 from cam 76 which, as described, forms a part of the repeater unit 75 actuated upon the original seizure of the line circuit. For example, if station G is transmitting through repeater 75 to station H, relay 67 is deenergized to close its back contact and in

so doing establishes an energizing circuit for relay 73 extending from grounded battery, normally closed contact 77, lower winding of relay 73, back contact and armature of relay 67, and front contact and armature of relay 68 to ground. Of course, upon the opening of the front contact of relay 67, the energizing circuit of the control electromagnet of repeater 75 will open and the cam drum thereof, on which cam 76 is mounted, is released for rotation. Upon the initial rotation of cam 76, contact 77 is opened and contact 78 is closed, whereupon the original energizing circuit of relay 73 is opened and a locking circuit for such relay is established extending from grounded battery, contact 78, upper winding and front contact of relay 73 to ground. Relay 73 is thus maintained energized for each cycle of operation of cam 76 and the repeater 75, and applies a shunt to the contacts of relay 68 so that even though such relay may follow the signals, it can exercise no control of the repeater, and consequently signals will not be impressed back on line 61. In this way, reflection of signals is prevented.

A modification of the system of Fig. 3 is disclosed in Fig. 4 in which terminal station G' is identical with the terminal station G of Fig. 3, in which a terminal station L constitutes a station equipped with apparatus arranged according to duplex circuit principles, and in which a repeating station N is equipped with a circuit system well known by the term half-duplex in which is embodied a start-stop regenerative repeater mechanism 85 arranged in some ways similar to the circuits of Fig. 3. As disclosed also in Fig. 3, terminal station G' has an individual line 86 extending to the repeating station N and terminating there in the winding of a line relay 87 which also has an associated seizing relay 88 which, as in Fig. 3, has an energizing winding whose circuit extends from battery through contact 90 controlled by cam 91, lower winding of seizing relay 88, back contact and armature of line relay 87 and ground, and a locking winding whose circuit extends from battery through contact 92 controlled by cam 91, upper winding of seizing relay 88, front contact and upper armature of relay 88 when energized, and to ground.

Terminal station L is equipped with a receiving printer 93 controlled by contacts of a polarized line relay 94 connected to line 95 and to artificial line 96 and through an interrupting key 97 to a transmitter 98. There is provided also a motor 99 for supplying a motive power to the transmitter 98 and receiving printer 93. Transmitter 98 normally connects line 95 to positive or marking battery but may connect the line to negative or spacing battery for the purposes of propagating telegraphic code signals over line 95, while interrupting key 97 normally connects line 95 to transmitter 98 and to positive battery, but when in its operated position connects the line 95 to negative or spacing battery instead for the purpose of producing an interrupting signal in line 95.

The terminal station L is connected by its individual line 95 to the repeating station N where it terminates in the winding of a polar line relay 101 which is connected also to an artificial line 102 and to an armature of a seizing relay 88 for a purpose to be described. There is associated with the polar line relay 101 a seizing relay 103 which also has an energizing winding whose circuit extends from battery through contact 90, lower winding of relay 103, normally open back contact

and armature of line relay 101, front contact and armature of line relay 87, and to ground, and a locking winding whose circuit extends from battery through contact 92 and upper winding of relay 103 and top contact and armature of relay 103, when energized, and to ground, the relay 103 having also a grounded armature and front contact for shunting the grounded armature and front contact of relay 87 thus rendering contacts of line relay 87 ineffective during the times that line relay 101 is operating and relay 103 is energized.

The regenerative repeater mechanism has operating magnet 104 connected in an operating circuit extending from battery through winding of magnet 104, front or normally closed contact and armature of polar line relay 101, and front contact and armature of line relay 87 to ground, and has also repeating contacts 105 and 106 which are convertible to be used either under principles of single-current transmission when relay 88 is deenergized or under principles of two-current transmission when relay 88 is energized, the repeating contacts 106 being open at the armature of relay 88 when the relay 88 is in deenergized condition. Seizing relay 103 when energized completes a circuit for single-current transmission from battery through repeating contacts 105, bottom armature and contact of operated seizing relay 103, winding of neutral line relay 87, line 86, and terminal station G' to ground, while seizing relay 88 when energized completes circuits for two-current transmission from positive or marking battery through repeating contacts 105 or alternatively from negative or spacing battery through front contact and middle armature of energized seizing relay 88 and repeating contacts 106, and thence extending for either current over front contact and bottom armature of energized seizing relay 88 to the apex of polar relay 101, line 95, to terminal station L, polar receiving relay 94, artificial line 96 and to ground, the relay 88 thus operating not only as a seizing relay to seize the regenerative repeater mechanism 85 but also as a converter to convert the regenerative repeater mechanism from single-current transmission principles to two-current transmission principles.

Terminal station G' desiring to transmit a message to terminal station L opens momentarily the interrupting key at terminal station G', thus opening the circuit of line 86 and starting the motor at terminal station G', also deenergizing line relay 87, which by opening its front contact deenergizes the operating magnet 104 of regenerative repeater mechanism 85 and starts the motor 107 and by closing its back contact closes the described energizing circuit of seizing relay 88, thus operating the relay 88 and connecting positive or marking battery through contact 105 to the apex of polar line relay 101 and connecting negative or spacing battery to repeating contacts 106, whereupon regenerative repeater mechanism 85 starts its cam 91 to close the locking circuit of seizing relay 88 and then to open the energizing circuit thereof and immediately the repeating contacts 105 and 106 are operated to repeat the spacing signal generated by the interrupting key at terminal station G' into line 95. The switching of the line 95 from marking battery on contacts 105 to spacing battery on contacts 106 reverses the polarity of current in line 95 and through polar receiving relay 94 to ground through artificial line 96, resulting in starting the motor 99 and in opening the contact of polar receiving relay 94 and deenergizing the magnet

93 of the receiving printer at terminal station L, thus repeating at terminal station L the interruption signal generated by the interrupting key at terminal station G'. Upon reclosing the interrupting key at terminal station G', line relay 87 becomes reenergized, magnet 104 of regenerative repeater mechanism 85 becomes reenergized, restoring marking current to line 95 and reversing polar receiving relay 94 which reenergizes magnet 93 of the receiving printer at terminal station L. Cam 91 stops at normal position shown and releases the locking circuit of seizing relay 88, thus completing the restoration to normal of all parts of the system. The motors having been started, the operator at terminal station G' may transmit a message to terminal station L. In each start-stop code combination of signal impulses, the starting impulse of spacing nature deenergizes line relay 87 and regenerative repeater magnet 104, and energizes and locks seizing relay 88, after which line relay 87 is controlled by contacts of the transmitter at terminal station G' under principles of single-current transmission, regenerative repeater magnet 104 is controlled by contacts of relay 87 under principles of single-current transmission, and polar receiving line relay 94 is controlled by regenerative repeater contacts 105 and 106 under principles of two-current transmission, while at the end of each code combination of impulses all parts of the repeating system are restored to their conditions of idleness.

Should the operator at terminal station L desire to interrupt the transmission, interrupting key 97 may be operated for a short period of time, thus impressing negative or spacing current upon line 95 and instantly the polar line relay 101 will respond and reverse the position of its armature, after which at the end of the instant code cycle and when cam 91 reaches its normal position and restores its contacts 90, the described energizing circuit of the seizing relay 103 will be completed, thus opening the circuit of line 86 which now will extend through winding of neutral line relay 87 and over front contact and bottom armature of seizing relay 103, through contact 106 to open contact of relay 88, it being borne in mind that the spacing condition of polar line relay 101 maintains its upper contact open and therefore maintains regenerative repeater magnet 104 deenergized and maintains regenerative repeater contacts 105 open and 106 closed, after which the receiving printer at terminal station G' will be unresponsive to its transmitter since no current can flow in line 86, by which non-responsive condition the operator at terminal station G' may be advised that terminal station L is interrupting and desires to transmit.

Terminal station L desiring to transmit a message to terminal station G' may operate interrupting key 97 which in its operated position switches line L from positive or marking battery to negative or spacing battery thus reversing the polarity of current in line 95 and starting the motor 99, also reversing the polarity of polar line relay 101 which by reversing the position of its armature and by opening its upper contact, deenergizes the operating magnet 104 of the regenerative repeater mechanism 85 and starts motor 107 and by closing its lower contact, closes the described energizing circuit of seizing relay 103, thus operating relay 103, after which the regenerative repeater mechanism 85 starts its cam 91 to close the locking circuit of seizing relay 103 and then to open the energizing circuit thereof,

and immediately the repeating contacts 105 are opened to repeat the spacing signal generated by interrupting key 97 at terminal station L into line 86. Opening line 86 deenergizes the magnet of the receiving printer and starts the motor at the terminal station G', thus repeating at terminal station G' the interruption signal generated by the interrupting key 97 at terminal station L. Upon restoring the interrupting key to normal at terminal station L, the polarity of current in line 95 becomes reversed, polar line relay 101 restores its armature, and magnet 104 of regenerative repeater mechanism 85 becomes reenergized, restoring marking current to line 86 and reenergizing the magnet of the receiving printer at terminal station G'. Cam 91 stops at normal position shown and releases the locking circuit of seizing relay 103, thus completing the restoration to normal of all parts of the system. The motors having been started, the operator at terminal station L may transmit a message to terminal station G'. In each start-stop code combination of signal impulses the starting impulse of spacing nature reverses the polarity of polar line relay 101 and deenergizes regenerative repeater magnet 104 and energizes and locks seizing relay 103, after which polar line relay 101 is controlled by contacts of transmitter 98 at terminal station L under principles of two-current transmission, regenerative repeater magnet 104 is controlled by contacts of line relay 101 under principles of single-current transmission, and the receiving printer at terminal station G' is controlled by regenerative repeater contacts 105 under principles of single-current transmission, while at the end of each code combination of signal impulses all parts of the repeating system are restored to their conditions of idleness. Should the operator at terminal station G' desire to interrupt the transmission, the interrupting key at terminal station G' may be operated for a short period of time, thus opening the circuit of line 86 whereupon but not until the end of the instant code combination of signals or not until the cam 91 has restored its contacts 90 and 92 to normal, the open line 86 will deenergize the line relay 87 which then will energize and operate its associated seizing relay 88 and will seize the regenerative repeater mechanism 85 to reverse the polarity of the current in line 95, whereupon polar receiving relay 94 instantly responds and opens its contact, thus deenergizing the magnet 93 of the receiving printer at terminal station L within which printer the cam drum 22, Fig. 1 will spin, which will constitute a signal to the operator at terminal station L that the operator at terminal station G' is interrupting and desires to transmit.

Reflection estoppel is effected in a manner identical with that described for Fig. 3; namely, through the control of relays 103 and 88, from cam 91, and contacts 90 and 92. Since the operation is similar to that for Fig. 3, repetition is not deemed necessary.

As disclosed in Fig. 5, the system of this invention may comprise two mechanically operated electrical switches for changing the connections of the regenerative repeater mechanism to render it responsive to one or the other of two line sections between which it functions. In Fig. 5, terminal stations G2 and H2 are identical in equipment and function with the terminal stations G and H of Fig. 3, each terminal station being connected to a repeating station P by a line 110 and 111 respectively, which terminate at the repeat-

ing station P in windings of two line relays 112 and 113 respectively, both line relays being normally in energized condition by current for line 110 over a line circuit extending from grounded battery through winding of a detector magnet 114, closed contacts of unoperated switch 115, winding of line relay 112, line 110, and terminal station G2 to ground, while for line 111 a similar circuit but not including the detector magnet 114 may be traced from grounded battery through resistor 116, closed contacts of unoperated switch 117, winding of line relay 113, line 111, and terminal station H2 to ground. It will be seen that both line relays 112 and 113 as well as the detector magnet 114 are held normally energized while the system is in condition of idleness, that if activity is initiated by opening line 110, both line relay 112 and detector magnet 114 will become deenergized simultaneously, but that if activity is initiated by opening line 111, the detector magnet 114 will not be deenergized immediately. The utility of this selective feature will appear in the description of operation of this embodiment of the invention.

A regenerative repeater mechanism 118 similar to mechanism 54, Fig. 2, is provided, its operating magnet 119 being included in a repeating circuit extending from grounded battery through winding of magnet 119, contacts of line relay 113, and contacts of line relay 112 to ground so that it may be controlled by either one of the two line relays 112 and 113 which in turn are controlled by the two terminal stations G2 and H2 respectively. Repeating contact 120 is connected in a normally open circuit extending from grounded battery through resistor 121 to the open left-hand contact member of switch 115 also to the open left-hand contact member of switch 117 from either of which two members the repeating circuit may be completed either by operation of switch 115 to complete the repeating circuit through winding of line relay 112, line 110, and terminal station G2 to ground or by operation of switch 117 to complete the repeating circuit through winding of line relay 113, line 111, and terminal station H2 to ground. Operation of switches 115 and 117 is effected by striker rods 121' and 122 respectively, which are operable alternatively by an operating member 123, which is positioned by the armature 124 of detector magnet 114 and is operated by cam follower lever 125 pivoted upon fixed pivot 126 and moved by cam follower 127 working in cooperation with cam 128 which is attached to cam drum 22, Fig. 1, of the regenerative repeater mechanism 118.

Armature 124 when attracted, holds cam follower lever 123 in position to operate rod 121' and when retracted, holds the cam follower lever in position to operate rod 122. Spring tension of contact members of switches 115 and 117 returns the rods to normalcy when not controlled by cam 128 and cam follower lever 125.

Operation of the structure disclosed in Fig. 5 is as follows, all magnets and relays shown being normally in energized condition by reason of currents in the several circuits described above. Assume that terminal station G2 desires to transmit a message to terminal station H2, the interrupting key at terminal station G2 may be operated momentarily, resulting in starting the motor at terminal station G2 and in deenergization of detector magnet 114 and of line relay 112, whose contacts deenergize regenerative repeater operating magnet 119 and start the motor of the regenerative repeater mechanism 118. Deener-

gization of magnet 114 has released its armature 124 which has moved the member 123 into position for operating rod 122 instead of rod 121', and the deenergization of the magnet 119 together with the starting of the motor of the regenerative repeater mechanism has started the cam 128, which controls cam follower 127, to rotate the follower arm 125 and operating member 123 which operates rod 122 and reverses the contactive relations of the contact members of switch 117, removing line 111 from its battery through resistor 116 and extending line 111 instead through the left-hand contact member of operated switch 17 to the repeating contact 120 and through resistor 121 to battery. Immediately the regenerative repeater mechanism 118 opens contact 120, thus opening line 111 and repeating into line 111 and to terminal station H2 the interruption signal of spacing nature generated by terminal station 20 G2. Upon reclosing the interrupting key at terminal station G2, the circuit of line 110 is closed, relay 112 and magnet 114 are reenergized, without moving armature 127, since operating member is positioned under the projecting end of rod 25 121' and is not allowed to rise, repeating magnet 119 is reenergized, and repeating contact 120 is reclosed, thus reclosing line 111 and repeating into line 111 and to terminal station H2 the marking signal generated at station G2, after which 30 cam 128 will complete its cycle of rotation and will stop, permitting follower 127 and follower lever 125 to return to normal and to return member 123, switch 117, and armature 124 to normal.

The motors having been started, the operator 35 at terminal station G2 may send a message to terminal station H2. Throughout the transmission of the message, a starting impulse of spacing nature in a start-stop code of signals will operate as has been described above for the spacing signal generated by the interrupting key, after which the separate and several signals of the ensuing code combinations of signals generated by the transmitter at terminal station G2 will control line relay 112, contacts of line relay 112 will 40 repeat the separate signals into magnet 119 of regenerative repeater mechanism 118 which then will repeat the separate signals by action of repeating contacts 120 through the line relay 113 into the line 111 and to the terminal station H2, 45 reflection signals being prevented by the right-hand contact members of operated switch 117 which shunt the contacts of the line relay 113. At the end of the start-stop code group of signals the transmitter at terminal station G2 will close 50 its contact to generate a stop signal of marking nature, cam 128 will complete its cycle, and the entire system will be restored to its condition of rest. Interruption of transmission may be effected by opening the interrupting key at terminal station H2 for a short period of time, thus 55 opening the circuit of line 111 whereupon, but not until the end of the instant code combination of signals or not until cam 128 has restored switch 117 to normal, the open line 111 will de- 60 energize line relay 113 which will seize the regenerative repeater mechanism in a manner to be described herein immediately below, after which the receiving printer at the terminal station G2 will be unresponsive to its transmitter since no 65 current can flow in line 110, by which non-response the operator at terminal station G2 may be advised that the operator at terminal station H2 is interrupting and desires to transmit. 70

Assume that terminal station H2 desires to transmit a message to terminal station G2, the

interrupting key at terminal station H2 may be opened momentarily, resulting in starting the motor at terminal station H2 and in deenergization of line relay 113 whose contacts deenergize regenerative repeater operating magnet 119 and start the motor of the regenerative repeater mechanism 118. Continued energization of detector magnet 114 maintains member 123 in position to operate rod 121', and the deenergization of magnet 119 together with the starting of the motor of the regenerative repeater mechanism has started the cam 128 which controls cam follower 127 to rotate the follower arm 125 and operating member 123 which operates rod 121' and reverses the contactive relations of the contact members or switch 115, removing line 110 from its battery through magnet 114 and extending line 110 instead through the left-hand contact members of operated switch 115 to the repeating contact 120 and through resistor 121 to battery. Immediately the regenerative repeater mechanism 118 opens contact 120, thus opening line 110 and repeating through relay 112 into line 110 and to terminal station G2 the interruption signal of spacing nature generated by the interrupting key at terminal station H2, reflection signals being prevented by the right-hand contacts of switch 115 which shunts the contacts of relay 112. Upon reclosing the interrupting key at terminal station H2, the circuit of line 111 is closed, relay 113 is reenergized, repeating magnet 119 is reenergized, and repeating contact 120 is reclosed, thus reclosing the circuit of line 110 and repeating into line 110 and to terminal station G2 the marking signal generated at the terminal station H2, after which cam 128 will complete its cycle of rotation and will stop, permitting follower 127 and follower lever 125 to return to normal and to return member 123, rod 121', and switch 115 to normalcy. The motors having been started, the operator at terminal station H2 may send a message to terminal station G2. Throughout the transmission of the message a starting impulse of spacing nature in a start-stop code of signals will operate as has been described above for the spacing signal generated by the interrupting key, after which the separate and several signals of the ensuing code combination of signals generated by the transmitter at terminal station H2 will control line relay 113, contacts of the line relay will repeat the separate signals into magnet 119 of regenerative repeater mechanism 118, which by its contact 120 will repeat the separate signals through the line relay 112 into line 110 and to the terminal station G2. At the end of the start-stop code group of signals the transmitter at terminal station H2 will close its contact to generate a stop signal of marking nature, cam 128 will complete its cycle, and the entire system will be restored to its condition of rest. Interruption by terminal station G2 of transmission from terminal station H2 may be effected in a manner similar to that described above for interruption by terminal station H2, the circuits involved in the interruption being already fully described above.

A direction-indicating mechanism in the printing equipment controlled by the regenerative repeating mechanism 118 and more specifically controlled by its cams 25, Fig. 1, for modifying the record to indicate the direction of transmission is illustrated in the form of a ribbon shifting device for using one or the other color of a two-color ribbon. Type 141 strikes ribbon 142 on its upper color band 143 when a pivoted arm 144

5 rests against its stop 145, thus holding ribbon 142 in its lower position. Shifting of pivoted arm 144 into contact with its stop 146 permits ribbon guide 147 to rotate upon fixed pivot 148 under tension of spring 149 to lift ribbon 142 into its upper position, thus bringing the second color band 151 of the ribbon into alignment with the type 141 so that the color of the record is changed in accordance with the position of the rocking arm 144. The change in position of pivoted arm 144 is attained by rocking a lever 152 on fixed pivot 153 when engaged by operating member 123 at lower or upper anvil 154 or 155, resulting in shifting the rocking lever 152 and pivoted arm 144 and their connecting link 156, the shifted elements being held in one or the other of their positions by jockey 157. It will be seen that the operating member 123 in its elevated position as shown moves to operate rod 121' and also will engage anvil 154 and will operate lever 152, link 156, and arm 144 into their upper positions to cause the type 141 to print through the lower color band 151, while when in its depressed position it moves to operate rod 122 and also will engage anvil 155 and will operate lever 152, link 156, and arm 144 into their lower positions to cause the type 141 to print through the upper color band 143. During the transmission described from terminal station G2 to terminal station H2, the type 141 and others, not shown, have operated to print utilizing the color band 143 of the ribbon 142 since operation of cam lever 123 with magnet 114 deenergized and with armature 124 retracted results in operation of switch 117 and engagement of cam lever 123 with anvil 155, thereby rocking the lever 152 into position shown, shifting link 156 downward and rocking lever 144 into engagement with its lower stop 145, thereby lowering ribbon 142 into position shown where type 141 strikes the upper color band 143. During transmission from terminal station H2 to terminal station G2, the type 141 has operated to print utilizing the color band 151 of the ribbon 142 since operation of member 123 with magnet 114 energized and with armature 124 attracted results in operation of switch 115 and engagement of member 123 with anvil 154, thereby rocking the lever 152, shifting the link 156 upward and rocking the lever 144 into engagement with the upper stop 146 which permits spring 149 to rotate ribbon guide 147 upon its fixed pivot 148, thereby lifting ribbon 142 into position where type 141 strikes the lower color band 151. Magnet 114 becomes deenergized by operation of switch 117 under control of terminal station H2 or by all spacing signals under control of terminal station G2, but at the end of each revolution of cam 128 the operated switch 115 or 117 is restored by cam 128 and magnet 114 is reenergized in preparation for a subsequent code cycle.

70 Reflection estoppel for the system of Fig. 5 is attained by providing electromagnet 114, which, through its armature 124, controls member 123 and the operation of rods 121 and 122. If transmission is from line 110 to line 111, relays 112 and electromagnet 114 will be energized and member 123 will be in the position shown in Fig. 5. Consequently, for each operation of cam 128, which is a part of the repeater, rod 121 will be operated and contacts 115 will be operated for applying current to the contact of relay 112, and thus effectively shunting its contacts so that even though its armature follows the signals it will exercise no control and signals will not be repeated back to the originating station.

In Fig. 6 are illustrated two regenerative repeater mechanisms 167 and 168 serving two sections of a single telegraph line and having a mechanical system of interlocking members. The drawing shows only the repeating equipment but the distant end of each line section 216 and 218 respectively may be provided with any conventional printing telegraph transmitting and receiving device.

Each repeater comprises identically the same parts bearing the same reference numerals except in the case of the repeater for line section 216 the reference numerals are distinguished from those applied to the parts of the repeater for line section 218 by a prime mark and includes a start-stop cam sleeve 171 carrying four cams; a starting cam 172, a latch restoring cam 173, an interlocking cam 174, and a signal cam 175 with cam lobes 177. A stop latch 181 upon a fixed pivot 182 engages cam 172 and restrains cam sleeve 171 against rotation by power communicated through a friction clutch. A start latch 183 is pivoted on pivot 182 and is restrained by its engagement with armature 184 while the armature is in its normal or marking position by energized magnet 185. Start latch 183 has striker 186 which may engage and operate stop latch 181 to disengage and release cam 172. Start latch 183 also has cam follower 187 operated by cam 173 to restore latch 183 after its release by armature 184.

Operation of these two latches under control of armature 184 is as follows: Upon deenergization of magnet 185 its armature 184 is released and is drawn by spring 191 into spacing position, thereby releasing start latch 183 which rotates under tension of spring 192 and causes lug 186 to engage and rotate latch 181 against the tension of spring 193, thus lifting latch 181 from cam 172 and releasing cam sleeve 171, 40 which then rotates and immediately causes cam 173 to engage and to operate follower 187 which rotates start latch 183 and lifts it and holds it clear of armature 184 throughout the then ensuing code period and until after the stop-signal impulse has been received.

Each cam sleeve 171 also has an interlocking cam 174 whose follower 195 operates a rocking lever 196, pivoted on one fixed pivot 197. Lever 196 is tensioned by a spring 199. At the other end of each lever 196, 196' is an interference lug 198 which, while in its operated position obstructs the armature 184 of an associated repeater and mechanically holds that armature in marking position.

Each cam sleeve 171 has also a signalling cam 175 having multiple lobes 177, one lobe for each individual signal impulse in a code cycle, seven being shown in the illustration of Fig. 6. The further structure of Fig. 6 will be more fully understood with reference to Patent 1,370,669 issued March 8, 1921, to L. M. Potts for Machine telegraph.

A signal lever 201 is pivoted loosely on a fixed pivot 202, is tensioned by spring 203 and is further supported by guides not shown. A contact lever 204 pivoted upon the fixed pivot 205 operates contacts 206 and is restrained by jockey 207. Signal lever 201 has two mechanical lugs 211 and 212 adapted to strike lever 204 to move it clockwise or counterclockwise selectively. Signal lever 201 has also a cam follower 213 cooperating with cam lobes 177 on cam 175 and has a pivot lug 214 adapted to be engaged and restrained by armature 184 in such manner that

when armature 184 is in marking condition the lug 214 is free to move and signal lever 201 is free to rotate upon its fixed pivot 202. When armature 184 is in spacing condition, the armature 184 engages the lug 214 and locks the lug end of the signal lever 201 so that the signal lever is not free to rotate upon its pivot 202 when actuated by a lobe 177 of cam 175 but must instead be lifted from its pivot against the tension of spring 203 and must rotate upon pivot lug 214 engaging armature 184 as a pivot.

Operation of signal lever 201 and of contact lever 204 is as follows: When actuated by cam 175 with armature 184 in marking position, lever 201 rotates upon pivot 202 and operates lug 212 to engage lever 204 to rotate lever 204 clockwise to close electrical contact 206 into marking condition as shown, the marking condition of contacts being then continued by jockey 207, or on the other hand, when actuated by cam 175 when armature 184 is in spacing condition, the signal lever 201 rotates upon pivot lug 214 with armature 184 as a pivot and operates lug 211 to engage and rotate lever 204 counterclockwise to open electrical contacts 206 into spacing condition, which condition is then maintained by jockey 207.

The two repeater mechanisms 167 and 168 are related mechanically through interlocking levers 196 and 196' and are further related electrically through circuits of two line sections. The line section conductor 216 is connected to upper contact 206' and an extension conductor 217 connects lower contact 206' to winding of magnet 185 connected to a source of current. The second line section conductor 218 is connected to upper contact 206 and an extension conductor 219 connects lower contact 206 to winding of magnet 185' connected to a source of current.

Operation of the entire system of Fig. 6 is as follows. A starting signal of spacing nature in first line section 216 deenergizes magnet 185, whereupon spring 191 draws armature 184 from under starting latch 183, which then is rotated on its pivot 182 by its spring 192 to cause its lug 186 to engage and to rotate latch 181 against tension of its spring 193 to lift latch 181 out of cam 172, thereby freeing sleeve 171 which rotates with its four cams, 172, 173, 174, and 175. Cam 173 by its follower 187 lifts latch 183 to clear armature 184, and cam 174 rotates lever 196 upon its pivot 197 to lift its lug 198 to engage armature 184', resulting in locking the armature 184' mechanically in its marking position, thus rendering the armature 184' unresponsive to tension of its spring 191' during the period lever 196 is operated. Cam 175 now operates one of its lobes 177 against cam follower 213 on lever 201, rotating the lever 201 upon its fixed pivot 202 through a very small angle until its pivot lug 214 engages retracted armature 184, after which the cam follower 213 rotates the lever 201 upon armature 184 as a pivot and against the tension of its spring 203, thereby lifting its lug 211 to engage and rotate lever 204 so that contacts 206 are released by lever 204. Contacts 206 become disengaged by their own spring tension and thus open the circuit of second line section 218, thus repeating in line section 218 the starting signal of spacing nature described. Opening the contacts 206 deenergizes magnet 185' but without effect since armature 184' is not now responsive to telegraphic signals manifested in magnet 185', it being locked

in its marking position by lug 198 in its operated position.

Each of the seven lobes 177 on cam 175 operates signal lever 201 which in turn may or may not operate lever 204 to change the condition of contacts 206 as required to repeat an instant received signal manifested in magnet 185. Should the instant received signal be of marking nature, armature 184 is attracted, lug 214 moves without engaging armature 184, lever 201 rotates on pivot 202, lug 212 engages and rotates lever 204, to close contacts 206 to produce a repeated marking signal in line section 218 unless the prior signal in line section 218 has been marking, in which case lever 204 is currently found in marking position and the operation of marking lug 212 is without effect. Should the instant signal in magnet 185 be spacing, armature 185 is retracted, lug 214 engages armature 184, lever 201 rotates upon armature 184 as a pivot, and spacing lug 211 engages lever 204 to operate contact 206 into open condition to produce a repeated spacing signal in line section 218 unless the prior signal in line section 218 has been spacing, in which case lever 204 will be currently in spacing or counterclockwise position and will remain in that position, spacing lug 211 thus operating without effect.

Selective action of lever 201 occurs seven times in each code cycle, first for the starting impulse, then for five character code impulses, then for a stop signal, after which the notch of cam 172 passes under latch 181 which by tension of its spring 193 engages the notch and stops the cam sleeve 171 with the notch of cam 173 positioned under cam follower 187 of latch 183 which latch thus is permitted to engage armature 184 in condition to receive a subsequent starting signal and with the notch of cam 174 under cam follower 195 of interlocking lever 196 so that spring 199 rotates lever 196 upon pivot 197 to withdraw lug 198 from armature 184. This completes a cycle of code transmission by control of line section 216 repeating into line section 218, and the operation of repeating into line section 216 by control of line section 218 and line magnet 185' is similar. Each signal impulse interval is timed in its beginning and ending by the several lobes 177 of cam 175 and is controlled as to marking or spacing nature by the operation of the armature of magnet 185 which is responsive at all times to the instant signal in a controlling line section.

Interruption in the transmission is effected by opening the receiving line section for an interval, whereupon during the stop signal condition of the transmitting line section the open circuit condition of the receiving line section will operate to seize the alternative repeating mechanism and to render the home recorder of the instant transmitting station unresponsive to the operating transmitter, thus notifying at the transmitting station that the then receiving station desires to transmit.

In Fig. 7 is shown motor control mechanism for the apparatus of Fig. 6 wherein a single motor drives either of the two associated repeating mechanisms and is controlled to start by a signal in either of the two associated line sections.

Upon a frame plate 231 are fixed brackets 232, 233 in which are journaled respectively shaft 234 carrying cam sleeve 171 driven through friction clutch 236 and shaft 234' carrying cam sleeve 171', driven through friction clutch 237. Latches 181 and 181' are fixed upon pivot rods 182, 182', 70 75

journaled in brackets 232 and 233 respectively, while latches 183, 183' are pivoted loosely upon pivot rods 182, 182'. Fixed also upon pivot rods 182 and 182' are cam followers 238 and 239 respectively, which follow screw thread cams 240 and 241 respectively. Cam 240 slides upon shaft 234, being at all times under tension of spring 242 and being rotated with the shaft 234 by spline 236'. Adjacent to cams 240 and 241 are snap switches 244 and 245 with operating arms 246 and 247 positioned to be engaged by flanges 248, 249, 250, and 251 fixed to cams 240 and 241. In operation, cam follower 238 which is without longitudinal movement, engages cam 240 by reason of rotation of pivot shaft 182. Rotation of shaft 234 will rotate cam 240 which, by reason of engagement with cam follower 238, will slide upon shaft 234 toward frame plate 231 until flange 248 engages arm 246 and moves arm 246 to reverse the mechanical condition of snap switch 244 to open its contacts 252.

A motor 254 driven from a source of power 255 when either contact 252 or 253 is closed operates through gears 256 to drive a common shaft 257, which through gears 258 drives shaft 234 and through gears 259 drives shaft 234'.

The operation of the motor control system in Fig. 7 is as follows. Receipt of a starting signal of spacing nature by line magnet 185 deenergizes the magnet and releases its armature 184 which by spring 191 is drawn from under latch 183, which rotates freely upon pivot shaft 182, and with its lug 186 engages latch 181, which rotates pivot shaft 182 and its cam follower 238, to lift the cam follower 238 away from the cam 240, thus releasing cam 240 which is propelled along shaft 234 by compression spring 242 until flange 250 engages operating arm 246 and operates snap switch 244 to close its contacts 252 which close an obvious circuit including source 255 and motor 254 so that the motor 254 is started and thereafter drives shafts 257, 234, and 234' continuously. Should the starting signal be received by magnet 185' instead, latch 183' would have been released to operate latch 181', pivot shaft 182' and cam follower 239 to release cam 241 which when operated under power of compression spring 243 would propel flange 251 to engage arm 247 to reverse the mechanical condition of snap switch 245 to close contacts 253, instead of 252, which would complete an obvious circuit to start motor 254, after which the motor would drive shafts 257, 234, and 234' continuously. Thereafter at each completion of a rotation of cam 172, latch 181 will engage the notch of cam 172, thereby rotating pivot shaft 182 to permit cam follower 238 to reengage cam 240, a disengagement being effected immediately upon receipt of the immediately succeeding start signal.

After the cessation of signalling, the absence of start signals will permit cam follower 238 to remain continuously in engagement with cam 240 for an interval sufficient for cam 240 to move along shaft 234 until its flange 248 engages arm 246 to reverse the mechanical condition of snap switch 244, thereby opening its contacts 252 to interrupt the circuit and to stop the motor 254.

When breaking, as described in connection with Fig. 6, the original transmission over controlling line section 216 will operate motor 254 by control of contacts 252 and the break under control of line section 218 will operate latch 181' and cam follower 239 to reverse the mechanical condition of snap switch 245 to close its points 253 so that for an interval motor 254 will have

its power circuit closed by contacts 252 and 253 in parallel. Each of the snap switches 244 and 245 will be reversed to open its contacts under control of its cam 240 or 241 by control of its own line section 216 or 218 and independently of the continuance or cessation of transmission under control of the associated line section, and the motor 254 may stop only when transmission has ceased upon both line sections for a suitable period.

According to the structure of Figs. 6 and 7, estoppel results from the fact that the armature of the repeating mechanism for the incoming line section is blocking mechanically, armature 184' being blocked by latch 196 when cam 174 is in rotated position in response to operation of armature 184.

Although the invention has been described in connection with a specific form thereof, it will be understood that it has further applications and it is not intended to be limited in scope by the embodiment shown herein for illustration.

The invention claimed is:

1. In a telegraph repeating system, two line sections, a line relay for each line section, an auxiliary relay for each line relay, a rotary repeating mechanism common to said line relays and operable initially by either of said line relays, and electrical contacts controlled by said rotary repeating mechanism after operation of one of said auxiliary relays to disable the other one of said auxiliary relays.

2. In a telegraph repeating system, two line sections, a line relay for each said line section, a rotary repeating mechanism common to said line relays and operable initially by a first actuated one of said line relays, a signal-receiving magnet and retransmitting contacts in said rotary repeating mechanism, and electrical contacts controlled by said rotary repeating mechanism after operation of said first actuated one of said line relays to associate said signal-receiving magnet with said first actuated one of said line relays and with its line section and to associate said retransmitting contacts with the other of said line sections.

3. In a telegraph repeating system, two line sections, a line relay for each said line section, a rotary repeating mechanism common to said line relays and operable by a first actuated one of said line relays, repeating electrical contacts in said rotary repeating mechanism and adapted to repeat received signals, and further electrical contacts controlled by said rotary repeating mechanism to associate said repeating contacts with the instantly unactuated one of said line relays.

4. In a telegraph repeating system, two line sections, a regenerative repeater mechanism having retransmitting contacts associated with said line sections and normally disconnected therefrom, mechanically operated means for operating said contacts, means for connecting said contacts

during their operation to either of said line sections to repeat into either of said line sections under control of received signals received from the other of said line sections, and means controlled by the starting signal impulse of a start-stop code of signalling conditions to determine the operation of said connecting means and thus the connection of said contacts to one of said two line sections and to effect such connection.

5. In a telegraph repeating system, two line sections, a single printing and regenerative repeating mechanism associated with said two line sections, circuits and switches between said mechanism and said two line sections and adapted to connect said mechanism between said two line sections in alternative manner to repeat impulses into either of said line sections alternatively under control of signalling conditions received from the other of said line sections, a pilot magnet controlled by one of said two line sections, and selectors controlled by said pilot magnet to select a desired switch.

6. In a telegraph repeating system, two line sections, a single printing and regenerative repeating mechanism associated with said two line sections, circuits and switches between said mechanism and said two line sections and adapted to connect said mechanism between said two line sections in alternative manner to repeat impulses into either of said line sections alternatively under control of signalling conditions received from the other of said line sections, a pilot magnet controlled by one of said two line sections, and selectors controlled by said pilot magnet to select a desired switch and to adjust printing elements in said mechanism to identify a selected switch.

7. In a telegraph repeating system, two line sections, a single printing and regenerative repeating mechanism associated with said two line sections, means adapted to connect said mechanism between said two line sections in alternative manner to repeat impulses into either of said line sections alternatively under control of signalling conditions received from the other of said line sections, and means controlled by one of said two line sections to determine the manner of connection.

8. In a telegraph repeating system, two line sections, a single printing and regenerative repeating mechanism associated with said two line sections, means adapted to connect said mechanism between said two line sections in alternative manner to repeat impulses into either of said line sections alternatively under control of signalling conditions received from the other of said line sections, and means controlled by one of said two line sections to determine the manner of connection and to modify a printing element in said mechanism to indicate the determined manner of connection.

LOUIS M. POTTS.
